FAN

William T. Dean, Gary, Ind.

Application July 22, 1938, Serial No. 220,812

3 Claims. (Cl. 230—209)

This invention relates to improvements in fan, and more particularly to those which are adapted for operation when exposed to temperatures such as are encountered in heating furnaces, although not limited thereto.

An object of this invention is to provide a fan adapted to operate in a furnace capable of maintaining temperatures in excess of 1400 degrees Fahrenheit for convection heating and controlling the distribution of the gases throughout the furnace.

Another object is to provide a fan or blower of heat resisting alloys so arranged as to make all parts, subjected to heat, self-cooling to a point well within the safe limits of the alloys used.

Other objects and advantages will become apparent as the description proceeds, in which:

Figure 1 is a transverse section of a convection heating furnace of the present invention; 20 Figure 2 is a section on line II—II of Figure 1; Figure 3 is a section on line III—III of Figure 4;

Figure 4 is a section on line IV—IV of Figure 3; and,

Figure 5 is a section on line V—V of Figure 3.

In the drawing, the numerals 2 and 3 represent the walls of a furnace which are constructed of refractory insulating brick for heat conservation and quick heating. The furnace bottom 4 may be of any desired construction, such as car bottom, solid bottom or conveyor bottom type. In any case, metallic material to be heat treated is supported above the bottom 4 by suitable alloy or refractory supports 5 of any desired construction, so as to permit the circulation of heated gases down through the material being treated and beneath the same in a horizontal direction, as indicated by the arrows in Figure 1, to the fan intake. The surplus gases 40 are bled off at this point through the dampered flues 6 into a main flue 7 to a stack connection (not shown) in the furnace wall.

The recirculated gases are exhausted from the furnace through the duct 8 into the fan 45 rotor, to be more fully hereinafter described, and discharged therefrom at a high velocity into the short flue 9, discharging horizontally into the top of the furnace through the Venturi-shaped opening 10.

Gas or oil is fed through the pipe 12 and mixes with air supplied through the pipe 14 to be combusted and mixed with the recirculated gases for discharge into the furnace through the Venturi-shaped opening 10. The opening 10 at the top of 55 the furnace, being Venturi-shaped, supplements

the velocity of the gases induced by the action of the fan rotor, so that upon entry into the upper portion of the furnace the gases have a high velocity. Combustion of the gases is completed in the upper portion of the furnace which is separated from the heating chamber 15 by an arch-shaped refractory partition member 16. This partition member 16 is provided with a plurality of perforations 17 extending therethrough; sized and arranged within said member 16 so as to provide for the uniform distribution of the products of combustion at a high velocity into the heating chamber 15 and uniformly over the entire surface of the metal being heat treated. 5

The means for withdrawing the gases from the heating chamber and recirculating the same comprises a fan constructed as shown in Figures 3 through 5. Suitably mounted in the wall of said furnace, in any conventional type of bearing support 18, is a hollow steel shaft 19 over which 20 is closely fitted an outer tube 20 of a suitable heat resisting alloy. Tubular driving-arms 21 of heat resisting alloy are welded at spaced intervals around the periphery of said tube 20. Impellers 22, formed from flat sheets of heat resisting alloy, are bent into U-shaped cross-section, as shown in Figure 4, with the free ends thereof forming a restricted duct or passageway 23. The U-shaped end portion of each impeller is provided with openings 24 in communication with 25 the ducts or passageways 25 formed between the outside diameter of said tubular driving-arms 21 and the disks 26 and 27 which close the ends of said U-shaped impellers 22 by being welded thereto, as illustrated at 28. Suitable openings 29 and 30 in the hollow shaft 19 and outer tube 20, respectively, coincide with the ducts or passageways 25 to permit circulation of cool air which has been drawn in from the outside through the hollow steel shaft 19 so that the cool air will 40 pass into the restricted duct or passageway 23 for discharge at the tip of said fan. Referring particularly to Figure 1 of the drawing, it will be perceived that the hot gases moving through the duct 8 will flow in the direction of the arrows 45 upwardly between the outer surface of the disk 27 and the adjacent inner surface of the furnace wall, which is slightly spaced therefrom. As the hot gases move upwardly across the outer surface of the disk 27 which, as shown more 50 clearly in Figure 3, is of solid construction, they are drawn upwardly into the short flue 9 by the air being discharged at the tip of the fan.

This design with proximity to the desired point of discharge for the hot gases permits the use 55

of relatively large diameters for the fan with low shaft speed, yet giving high velocity to the air and hot gases to be moved. The operation of the fan, which may be in any conventional manner to set up the required flow of hot gases also sets up a flow of external cold air through the hollow shaft. This air is discharged at the fan tips, mixing with the hot gases, and, by the amount of air so passed, reduces the combustion air required without affecting the reducing atmosphere within the heating chamber. In a typical case it was found that with 1 per cent. of the required combustion air passed through the impellers as a cooling medium, the temperature of the impellers was limited to less than 1200 degrees Fahrenheit when handling gases at 1650 degrees Fahrenheit.

Since the fan of the invention is necessarily of the overhung type, the large diameter hollow shaft operating at low shaft speed is ideally suited to the required service as it eliminates bearings in the bath of hot gases. Preferred bearings are of the synthetic-resin-cotton water-lubricated type, further tending to limit maximum temperatures to which the shaft may be subjected.

Combustion air for furnaces of the type herein described must be supplied under slight pressure to assist in the recirculation action and to provide for complete combustion control.

In a furnace of the type described, the overall thermal efficiency may be extremely high due to rapid even heating of the charge coupled with excellent insulation and good recuperation, while surface scaling and alteration in grain size may be strictly limited: the first by entire absence of free oxygen, the latter by limited maximum temperatures and short treating time.

While I have shown and described specific embodiments of the invention, it will become apparent that I do not wish to be limited exactly thereto, since various modifications may be made without departing from the scope of the invention, as defined by the appended claims.

I claim:

1. A fan comprising a hollow shaft having circumferentially and axially spaced openings on its periphery, and a plurality of impeller blades secured between parallel spaced plates and 5 radially disposed about said shaft between said axially spaced openings, each of said impeller blades including an innermost closed tubular member and a U-shaped outer tip member, said innermost member forming with the spaced 10 plates passageways in alignment with the said spaced openings in said hollow shaft, whereby cool air is directed only to the tip of each of said impeller blades.

2. A fan comprising a hollow shaft having circumferentially and axially spaced openings, spaced parallel plates secured to said hollow shaft, and heat-resistant impeller blades positioned between said spaced plates and arranged radially about said hollow shaft, said impeller 20 blades including closed tubular members secured to said shaft between said axially spaced openings to form with said spaced plates passageways in alignment with the spaced openings in said hollow shaft, and U-shaped tip members secured to 25 said closed tubular members and said spaced plates and provided with openings in communication with said passageways so as to direct cool air to the tip of each impeller blade.

3. A fan comprising a hollow shaft, a plurality 30 of impeller blades secured between parallel spaced plates and radially disposed about said hollow shaft; each of said impeller blades having a closed chamber terminating inwardly of its outer end, and means disposed exteriorly of said 35 chambers but between said parallel spaced plates for permitting the passage of air to the outer ends of said impeller blades, said hollow shaft having apertures communicating with said means.

WILLIAM T. DEAN.
